Primary Examiner — Eric Goodman*Assistant Examiner* — Christian P McLean(74) Attorney, Agent, or Firm — Banner & Witcoff, Ltd.(57) CLAIM

The ornamental design for a display screen with graphical user interface, as shown and described.

DESCRIPTION

FIG. 1 is a front view of a display screen with graphical user interface showing our new design;

FIG. 2 is a front view of the display screen of FIG. 1 shown on a device thereof;

FIG. 3 is a rear view of the device thereof;

FIG. 4 is a left side view of the device thereof;

FIG. 5 is a right side view of the device thereof;

FIG. 6 is a top view of the device thereof; and,

FIG. 7 is a bottom view of the device thereof.

The broken line showing of the remainder of the user interface, the remainder of the display screen, and the device is for environmental purposes only and forms no part of the claimed design.

1 Claim, 4 Drawing Sheets# US D765,696 S
